CLAIM

We claim the ornamental design for a pair of fuel junction blocks, as shown and described.

DESCRIPTION

FIG. 1 is an isometric view of the right side fuel junction block of the pair of fuel junction blocks, looking downwardly toward the top;

FIG. 2 is a right side view of FIG. 1;

FIG. 3 is a left side view of FIG. 1;

FIG. 4 is a front view of FIG. 1;

FIG. 5 is a back view of FIG. 1;

FIG. 6 is a top view of FIG. 1; and,

FIG. 7 is a bottom view of FIG. 1.

The design is a fuel junction block that is used with a commercial vehicle fuel tank. A left hand version is used with a left hand fuel tank of the commercial vehicle and a right hand version is used with a right hand fuel tank of the commercial vehicle. The left hand version and the right hand version of the fuel junction block are mirror images of one another. The design claimed in this design patent covers both left and right hand versions of the fuel junction block even though only one version is shown for ease of illustration.

The left side fuel junction block of the pair of fuel junction blocks is a mirror image of the right side fuel junction block. Only the right side fuel junction block of the pair of fuel junction blocks has been illustrated for ease of illustration.
